HANDLE FOR ABRASIVE TOOLS AND THE LIKE

William McMahon, 603 Victor Ave., Anaheim, Calif.
92801, and William F. Hamman, 9601 Imperial Ave.,
Garden Grove, Calif. 92641

Filed Feb. 9, 1970, Ser. No. 21,368

Term of patent 14 years

Int. Cl. D8—02

U.S. Cl. D8—94

Fig. 1.

Fig. 2.

Fig. 3.

Fig. 4.

Fig. 5.

FIG. 1 is a perspective view of a handle for abrasive tools and the like showing our new design;

FIG. 2 is a rear elevational view of our design;

FIG. 3 is a side elevational view thereof which is not shown in FIG. 1;

FIG. 4 is a sectional view of our new design taken on line 4—4 of FIG. 2; and

FIG. 5 is also a sectional view taken on line 5—5 of FIG. 2 thereof.

We claim:

The ornamental design for a handle for abrasive tools and the like, as shown.
